SPINNING APPARATUS

Leopold Cizek, Erik Jirasek, Frantisek Bucil, and Josef Ripka, Usti N. Orl., Czechoslovakia, assignors to Vyzkumny Ustav Bavinarsky, Usti N. Orl., Czechoslovakia

Filed Sept. 18, 1962, Ser. No. 227,977
20 Claims. (Cl. 57—58.91)

The present invention relates to a spinning apparatus, and more particularly to an apparatus for drawing and twisting rovings to form a yarn.

The ring spinning method in which the roving passes through drawing rolls and through an eye to the spinning ring on which the traveler revolves has a limited output since the speed of the traveler cannot be increased above a certain limit, and furthermore it is not possible to prevent balloon forming during high speed operations.

Other spinning apparatus is known in which air is used for the transport of the rovings, but these devices require a separate machine for producing compressed air, or for producing a negative suction pressure.

In another spinning apparatus, the twisting member is used for producing the air stream, and this apparatus has the disadvantage that the suction depends on the speed of rotation of the twisting means.

Other spinning devices use electrostatic field or centrifugal force for achieving a parallel position of the rovings on a rotary surface. In accordance with one construction of the prior art, the deposited material is twisted by a rotating disc having an eccentric aperture through which the finished yarn passes. Another known spinning apparatus uses two crossed belts for twisting the rovings. However, the thickness and twist of yarn produced by the apparatus of the prior art is not exactly uniform.

It is one object of the present invention to provide a spinning apparatus which consists of few parts, operates reliably, has a high output, and produces uniformly twisted yarn of constant thickness.

Another object of the invention is to provide spinning apparatus in which the rovings are divided into fibers which are supplied to the twisting means in a parallel position so that the finished yarn has a uniform structure.

Another object of the present invention is to provide a spinning device in which the roving is drawn and divided by an air stream whose speed and drawing action is independent of the speed of rotation of the twisting means.

With these objects in view, one embodiment of the spinning apparatus according to the invention comprises supply means for supplying rovings, a rotary suction and drawing means having an inlet communicating with the supply means and at least one outlet, and which is so constructed that upon rotation of the drawing means a stream of air passes from the inlet to the outlet to divide the rovings into fibers and to blow the same through the outlet means, and a rotary spinning or twisting means having a revolving surface located opposite the outlet. The fibers are thus deposited on the revolving surface, and are guided through a centrally located guide means which either rotates with the twisting means, or is stationary. In this manner, a twisted yarn is produced.

In the preferred embodiment of the invention, the roving is supplied into one end of a stationary tube which is continued by a rotary tubular part of the drawing means so that a continuous inlet duct for the roving, the fibers, and for a stream of air is formed. The air is sucked into the aligned tubes since the rotary suction and drawing means has radial outlet passages in which the air is forced to flow in an outward direction during rotation of the drawing means.

In one embodiment of the invention the spinning or twisting means has a bowl-shaped portion merging into

2

a central tubular portion which forms a rotating guide means for the twisted yarn which is transported by a pair of transporting rollers. The wide open end of the bowl-shaped twisting means forms an outlet for the air passing through the outlets of the drawing means and carrying the fibers to the portion of the inner surface of the twisting means on which the rovings are deposited.

In another embodiment of the invention, the spinning or twisting means is ring-shaped and has a circular inner surface which is curved in axial planes, and which may form part of a spherical surface. The fibers are deposited on this surface, and guided through a guide means located in the axis of rotation of the rotary twisting means so that the fibers are twisted into a yarn.

The rotary suction and drawing means, and the rotary spinning or twisting means rotate at different speeds, or in opposite directions to obtain a uniform distribution of the fibers in parallel positions on the revolving surface of a twisting means.

The novel features which are considered as characteristic of the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a fragmentary sectional view of a spinning apparatus according to one embodiment of the invention:

FIG. 2 is a fragmentary sectional view of a spinning apparatus according to another embodiment of the invention: and

FIG. 3 is an exemplary embodiment of the apparatus including the winding up means and drive.

Referring to FIG. 1, a pair of feeding rollers 1 supplies the roving into the tapered end 4 of a stationary tube 3 whose other wider end is secured to a sleeve 6. A rotary suction and drawing means 2 has a tubular part 5 whose end is located in sleeve 6, and forms a continuation of the fixed tube 3. The other end of the drawing means 2 has two radially projecting arms with outlet passages 9 extending in opposite directions transverse to the axis of rotation of the drawing means 2. When suction and drawing means 2 are rotated, air is forced out of the outlet passages 9, and drawn through the aligned and coaxial tubes 3 and 5 so that the roving is drawn and fibers 18 are loosened from the roving at 10 in the tube 3, and blown out of the outlets 9.

The lower end portion of the rotary drawing means 2 is located in a bowl-shaped portion of a spinning or twisting means 7 which has a circular collecting surface 8 located opposite the outlets 9 so that the blown out fibers are deposited on this surface. The surface is preferably also curved in axial planes so that its shape is part-spherical. However, the inner surface of the chamber in the spinning or twisting means 7 may also be conical or of oval shape. The inner surface of a tubular portion 12 merges into the inner surface of the bowl-shaped portion 7, the tubular portion 12 being concentric with the axis of rotation of the twisting means 7, 12. The fibers deposited on the revolving surface 8 form a ring 19 due to the relative movement between the inner circular collecting surface 8 and the outlets 9. In the preferred embodiment of the invention, the drawing means 2 rotates in opposite direction to the sense of rotation of the twisting means 7, 12. The bowl-shaped portion of the twisting means 7 has a circular edge surrounding the tubular portion 2 and defining with the same a circular outlet opening 15 through which the air blown out of passage 9 escapes. A plurality of openings may be provided instead of a single opening.

The spinning and twisting apparatus illustrated in FIG. 1 is operated as follows:

A roving S is supplied by feed rollers 1 into the tapered end 4 of the fixed tube 3. Due to the rotation of the suction and drawing means 2, an air stream is sucked into the opening in the end portion 4 and passes out of the outlets 9. Negative pressure is thus produced in tube 3, and fibers 18 are loosened from the bunched roving portion 10 in the stationary tube 3 and carried with the air stream through the rotating tube and outlets 9 to the revolving collecting surface 8 which moves relative to the rotating outlets 9. Since the end portion 4 is constricted, the air moves very rapidly at the inlet end of the tube 3, and exerts a strong loosening action on the roving 10 which is divided into fibers. The released fibers 18 flow in the air stream until they are thrown through passages 9 onto the revolving surface 8 where they are deposited in parallel positions and are formed into a ring-shaped body 19 which is pressed against the collecting surface 8 by the centrifugal force. The rotary action of the twisting means 7 results in a continuous rolling of the fibers and a twisted yarn is formed which is moved along wall 11 and through the tubular guide portion 12 by the transporting rollers 13 when the spinning element adheres to the fibers 19. The air passing out of outlet passages 9 is discharged through the outlet opening 15.

The embodiment of FIG. 2 corresponds in all constructive features to the embodiment of FIG. 1, with the exception of the spinning and twisting means. A ring 16 surrounds the part of the drawing means 2 which has the outlets 9, and has an inner collecting surface 8' which is substantially part-spherical. Instead of the rotary tubular guide means 12 of the embodiment of FIG. 1, a stationary guide means 17 is provided whose opening is located on the axis of rotation of the rotary twisting means 16 and of the rotary drawing means 2.

The operation of the embodiment of FIG. 2 is the same as described with reference to FIG. 1, and the fibers are deposited in a ring-shaped body 19 on the revolving surface 8' when suction and drawing means 2 and spinning means 16 rotate in opposite directions. The twisted yarn 14 passes through the opening in the stationary guide means 17 and is transported by the transporting rollers 13.

As shown in FIG. 3 all mechanism and their drives are secured to a carrier frame 30. Fixed to the upper part of the frame 30 is a holder 20 for the feeding rollers 1 with a pulley 53. In a downward direction there follow further parts: a stationary part 3 of the feeding tube consisting of two pieces and secured to a sleeve 6 mounted on the holder 21; and further a rotary part 5 of the feeding tube, said part being mounted for rotation in a bearing body 22. A pulley 49 is keyed on to said feeding tube. Channels provided in the rotary part 5 of the feeding tube lead to a rotary twisting chamber 7 mounted for rotation in a bearing body 23, a pulley 47 being keyed on to said chamber. Below the rotating twisting chamber 7 transporting rollers 13 are accommodated and connected to a pulley 43 provided on a holder 24 and below the rollers 13 there is arranged the winding up means 25 for the yarn 14 comprising a driving roller 31, a pulley 39 and a pressure arm 32 carrying the bobbin 33 with wound yarn. Accommodated at the other side of the frame 30 is an electric motor 35 with a pulley 36 which drives the apparatus with the aid of further driving means, such as belts 54, 55, 56, 57, 58, 59, 60, 61, 62, pulleys 37, 38, 40, 41, 42, 44, 45, 46, 48, 59, 51, 52, shafts 63, 64, 65, 66 and shaft holders 26, 27, 28, 29.

The apparatus is driven by an electric motor 35 whose torque is transmitted by the pulley 36 and belt 54 to the pulley 37 arranged on a shaft 65. From the shaft 65 movement is derived by means of the pulley 38, belt 55 and pulley 39 to the driving roller 31 of the winding up means 25 and further by the pulley 40, belt 56 and pulley 41 to a countershaft 63. From the countershaft 63

movement is transmitted by the pulley 42 and belt 57 to the pulley 43 of the transporting rollers 13. The pulley 50, belt 61, pulleys 51, 52, keyed on to the shaft 66, and belt 62 serve to drive the pulley 53 of the feeding rollers 1. The pulley 44 and the crossed belt 58 serve to drive the pulley 45 of the countershaft 64. From the countershaft 64 the drive is transmitted over the pulley 46, belt 59 and pulley 47 to the rotary twisting chamber 7. The pulley 48, crossed belt 60 and pulley 49 drive the rotary part 5 of the two-piece feeding tube. Fibrous material supplied in a roving S by the feeding rollers 1 is conveyed by the air stream produced due to the rotation of the rotary part 5 of the two-piece feeding tube through the stationary part 3 and rotating part 5 of the feeding tube into the revolving twisting chamber 7, where the material is deposited in the way described above.

From the revolving twisting chamber 7 the yarn 14 is withdrawn by the transporting rollers 13 and wound on a cylindrical bobbin 33 which, together with the wound-up yarn 34, is driven by the driving roller 31 provided with a groove serving for the distribution of the yarn along the bobbin 33.

It will be understood that each of the elements described above, or two more together, may also find a useful application in other types of spinning apparatus differing from the types described above.

While the invention has been illustrated and described as embodied in a spinning apparatus including a rotary drawing means producing a stream of air, and a rotary twisting means surrounding a part of the drawing means, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A spinning apparatus comprising, in combination, supply means for supplying rovings and including a stationary tube; a rotary suction and drawing means rotating about an axis and having inlet means communicating with said stationary tube and outlet means transverse to said axis of rotation so that upon rotation of said suction and drawing means the rovings drawn by an air stream into said inlet means are disintegrated and divided into fibers therein and are blown as loose fibers through said outlet means; and a rotary spinning means having a revolving surface located opposite said outlet means and moving relative to the same so that the fibers are deposited on said surface and twisted to form a twisted yarn.

2. A spinning apparatus comprising, in combination, supply means for supplying rovings and including a stationary tube; a rotary suction and drawing means rotating in one direction of rotation about an axis and having inlet means communicating with said stationary tube and outlet means transverse to said axis of rotation so that upon rotation of said drawing means the rovings drawn by an air stream into said stationary tube are disintegrated and divided into fibers therein and are blown as loose fibers through said outlet means; and a rotary spinning means rotating in a direction opposite to said direction of rotation and having a revolving surface located opposite said outlet means and moving relative to the same so that the fibers are deposited on said surface and twisted to form a twisted yarn.

diameter as said supply tube and extending to the other end of said supply tube and communicating with the same, said suction and drawing means having outlet passages extending transverse to said axis of rotation so that upon rotation of said suction and drawing means, the rovings drawn by an air stream through said supply tube and said tubular portion are disintegrated and divided into fibres in said stationary supply tube by the reduced pressure in said stationary supply tube and are blown as loose fibres through said outlet means; rotary twisting means rotating relative to said rotary suction and drawing means about an axis of rotation coinciding with said axis of rotation of said suction and drawing means, and having a revolving surface located opposite said outlet passages and moving relative to the same so that the fibres passing through said outlet passages are deposited on said surface and twisted to form a twisted yarn; guide means located in the region of said axes for guiding the twisted yarn; and transporting means for transporting the twisted yarn through said guide means.

11. A spinning apparatus comprising, in combination, a stationary supply tube having an axis; means for feeding rovings into one end of said supply tube; a rotary suction and drawing means having an axis of rotation coinciding with said axis, said rotary suction and drawing means having a central tubular portion having the same diameter as said supply tube and extending to the other end of said supply tube and communicating with the same, said suction and drawing means having outlet passages extending transverse to said axis of rotation so that upon rotation of said suction and drawing means, the rovings drawn by an air stream through said supply tube and said tubular portion are disintegrated and divided into fibres in said stationary supply tube by the reduced pressure in said stationary supply tube and are blown as loose fibres through said outlet means; rotary twisting means rotating relative to said rotary suction and drawing means about an axis of rotation coinciding with said axis of rotation of said suction and drawing means, and having a revolving surface located opposite said outlet passages and moving relative to the same so that the fibres passing through said outlet passages are deposited on said surface and twisted to form a twisted yarn, said rotary twisting means having an axially extending tubular guide portion for guiding the twisted yarn; and transporting means for transporting the twisted yarn through said tubular guide portion.

12. A spinning apparatus comprising, in combination, a stationary supply tube having an axis; means for feeding rovings into one end of said supply tube; a rotary suction and drawing means having an axis of rotation coinciding with said axis, said rotary suction and drawing means having a central tubular portion having the same diameter as said supply tube and extending to the other end of said supply tube and communicating with the same, said suction and drawing means having outlet passages extending transverse to said axis of rotation so that upon rotation of said suction and drawing means, the rovings drawn by an air stream through said supply tube and said tubular portion are disintegrated and divided into fibres in said stationary supply tube by the reduced pressure in said stationary supply tube and are blown as loose fibres through said outlet means; rotary twisting means rotating relative to said rotary suction and drawing means about an axis of rotation coinciding with said axis of rotation of said suction and drawing means, and having a revolving surface located opposite said outlet passages and moving relative to the same so that the fibres passing through said outlet passages are deposited on said surface and twisted to form a twisted yarn, said twisting means having at least one opening adjacent said revolving surface for the discharge of air; guide means located in the region of said axes for guiding the twisted yarn; and transporting means for transporting the twisted yarn through said guide means.

13. A spinning apparatus comprising, in combination, a stationary supply tube having an axis; means for feeding rovings into one end of said supply tube; a rotary suction and drawing means having an axis of rotation coinciding with said axis, said rotary suction and drawing means having a central tubular portion having the same diameter as said supply tube and extending to the other end of said supply tube and communicating with the same, said suction and drawing means having outlet passages extending transverse to said axis of rotation so that upon rotation of said suction and drawing means, the rovings drawn by an air stream through said supply tube and said tubular portion are disintegrated and divided into fibres in said stationary supply tube by the reduced pressure in said stationary supply tube and are blown as loose fibres through said outlet means; a rotary twisting means having at one end a revolving surface and at the other end a tubular guide portion, and an inner surface connecting said revolving surface with the interior of said tubular guide portion, said circular revolving surface surrounding the portion of said rotary suction and drawing means in which said outlet passages are located and moving relative to the same so that fibres passing through said outlet passages are deposited on said surface and are twisted to form a twisted yarn passing through said tubular guide portion; and transporting means at the end of said tubular guide portion for transporting the twisted yarn.

14. A spinning apparatus comprising, in combination, a stationary supply tube having an axis; means for feeding rovings into one end of said supply tube; a rotary suction and drawing means having an axis of rotation coinciding with said axis, said rotary suction and drawing means having a central tubular portion having the same diameter as said supply tube and extending to the other end of said supply tube and communicating with the same, said suction and drawing means having outlet passages extending transverse to said axis of rotation so that upon rotation of said suction and drawing means, the rovings drawn by an air stream through said supply tube and said tubular portion are disintegrated and divided into fibres in said stationary supply tube by the reduced pressure in said stationary supply tube and are blown as loose fibres through said outlet means; a rotary twisting means rotating about an axis of rotation coinciding with said axis of rotation of said suction and drawing means and relative to said suction and drawing means, said twisting means having at one end a circular revolving surface concentric with said axis and at the other end a tubular guide portion concentric with said axis and having a diameter smaller than the diameter of said revolving surface, and an inner surface connecting said revolving surface with the interior of said tubular guide portion, said circular revolving surface surrounding the portion of said rotary suction and drawing means in which said outlet passages are located and moving relative to the same so that fibres passing through said outlet passages are deposited on said surface and are twisted to form a twisted yarn passing through said tubular guide portion; and transporting means at the end of said tubular guide portion for transporting the twisted yarn.

15. A spinning apparatus as set forth in claim 14 wherein said circular revolving surface is curved in axial planes and defines an outlet opening for air with said central tubular portion of said suction and drawing means.

16. A spinning apparatus as set forth in claim 14 and including a sleeve fixed to said other end of said supply tube and surrounding the end of said central tubular portion of said suction and drawing means.

17. A spinning apparatus comprising, in combination, a stationary supply tube having an axis; means for feeding rovings into one end of said supply tube; a rotary suction and drawing means having an axis of rotation coinciding with said axis, said rotary suction and drawing means having a central tubular portion having the same

diameter as said supply tube and extending to the other end of said supply tube and communicating with the same, said suction and drawing means having outlet passages extending transverse to said axis of rotation so that upon rotation of said drawing means, the rovings drawn by an air stream through said supply tube and said tubular portion are disintegrated and divided into fibres in said stationary supply tube by the reduced pressure in said stationary supply tube and are blown as loose fibres through said outlet means; rotary twisting means rotating relative to said rotary suction and drawing means about an axis of rotation coinciding with said axis of rotation of said suction and drawing means and having a revolving surface located opposite said outlet passage and moving relative to the same so that the fibres passing through said outlet passages are deposited on said surface and twisted to form a twisted yarn; a fixed guide means located in the region of said axes for guiding the twisted yarn; and transporting means for transporting the twisted yarn through said guide means.

18. A spinning apparatus comprising, in combination, supply means for supplying rovings and including a stationary tube; a rotary suction and drawing means rotating about an axis and having inlet means communicating with said stationary tube and outlet means transverse to said axis of rotation so that upon rotation of said suction and drawing means the rovings drawn by an air stream into said stationary tube are disintegrated and divided into fibres therein and are blown as loose fibres through said outlet means; a rotary twisting means having a revolving surface concentric with said axis located opposite said outlet means and moving relative to the same so that the fibres are deposited on said surface and twisted to form a twisted yarn; guide means for guiding the twisted yarn from said surface to a position located in the said axis; and transporting means for transporting the twisted yarn through said guide means.

19. A spinning apparatus comprising, in combination, supply means for supplying rovings and including a stationary tube; a rotary suction and drawing means rotating about an axis and having inlet means communicating with said supply means and outlet means transverse to said axis of rotation so that upon rotation of said suction and drawing means the rovings drawn by an air stream into said inlet means are disintegrated and divided into fibres therein and are blown as loose fibres through said outlet means; a rotary twisting means having a revolving surface concentric with said axis located

opposite said outlet means and moving relative to the same so that the fibres are deposited on said surface and twisted to form a twisted yarn; guide means for guiding the twisted yarn from said surface to a position located in the said axis; and transporting means for transporting the twisted yarn through said guide means, said twisting means having an outlet for air adjacent said revolving surface.

20. A spinning apparatus comprising, in combination, 10 a stationary supply tube having an axis and a length adapted to be at least equal to the maximal length of fibers to be spun; means for feeding rovings into one end of said supply tube; a rotary suction and drawing means having an axis of rotation coinciding with said axis, said 15 rotary suction and drawing means having a central tubular portion having the same diameter as said supply tube and extending to the other end of said supply tube and communicating with the same, said suction and drawing means having outlet passages extending transverse to 20 said axis of rotation so that upon rotation of said suction and drawing means, the rovings drawn by an air stream through said supply tube and said tubular portion are disintegrated and divided into fibres in said stationary supply tube by the reduced pressure in said stationary supply tube and are blown as loose fibres through said 25 outlet means; rotary suction and twisting means rotating relative to said rotary drawing means about an axis of rotation coinciding with said axis of rotation of said suction and drawing means, and having a revolving surface located opposite said outlet passages and moving relative to the same so that the fibres passing through said outlet 30 passages are deposited on said surface and twisted to form a twisted yarn; guide means located in the region of said axes for guiding the twisted yarn; and transporting 35 means for transporting the twisted yarn through said guide means.
